H. HARGER.
TYPE SETTING MACHINE.

No. 28,857.

Patented June 26, 1860.

Inventor:

Henry Harger

UNITED STATES PATENT OFFICE.

HENRY HARGER, OF DELHI, IOWA.

MACHINE FOR SETTING TYPE.

Specification forming part of Letters Patent No. 28,857, dated June 26, 1860.

To all whom it may concern:

Be it known that I, HENRY HARGER, of Delhi, in the county of Delaware and State of Iowa, have invented a new and Improved Type-Setting Machine; and I do hereby declare that the following is a full, clear, and exact description of the same, reference being had to the annexed drawings, making a part of this specification, in which—

Figure 1 is a plan or top view of my machine. Fig. 2 is a vertical longitudinal section of the same, taken in the line $y y$, Fig. 1. Fig. 3 is a transverse vertical section of the same, taken in the line $x x$, Fig. 1.

Similar letters of reference indicate corresponding parts in the several figures.

This invention consists of an arrangement of machinery in connection with the type-case by which the type are fed to the composing-stick, and of an arrangement of levers and fingers in connection with the composing-stick, by means of which the type may be readily taken from the case and set in line.

To enable those skilled in the art to fully understand and construct my machine, I will proceed to describe it.

A is a frame made in any suitable manner to support the working parts of the device.

A' is the front part.

B is a type-case. It is divided into compartments $b b$ by strips of brass plate or other suitable material. These compartments must correspond in number with the characters that are to be set by the machine. They may be of any required length. Their depth is about two-thirds of the length of the type or sufficient to keep the type in an upright position, their width such as to allow the line of type to move easily along from one end to the other. The front end of each of these compartments has an opening at the bottom, through which the type are discharged into the composing-stick. These openings are arranged in an arc of a circle whose center is at i , Figs. 1 and 2. In each of these compartments is a follower C, for the purpose of feeding up the type to the front end of the compartment as they are needed. This is an upright or slightly-inclined piece of metal of such a width as to move easily along the compartment. It has a horizontal arm C', which slides on the bottom of the compartment, with teeth so arranged as to allow it to move easily

toward the front part of the machine, but to prevent its being moved in the opposite direction by the action of the machinery, as shown in Fig. 2. The follower C has also an arm c with ratchet-teeth, as shown in Fig. 2. These teeth correspond in width with the letter that is to be placed in the compartment.

There is a rod D, Figs 2 and 3, under each compartment, which works back and forth lengthwise of the compartment.

There is a pawl E in each compartment turning on a pivot at e . Its lower end is attached to the rod D by a hinge-joint, and its upper end works in the ratchet-teeth of the arm c.

F is a spring, which tends to throw the rod D toward the front end of the machine.

Each compartment has a finger G at the front end for the purpose of steadyng the type until pushed by it by the follower C. It is made by cutting a strip of metal in the side of the compartment, so that its front end may be bent slightly into the compartment, while its hinder end remains attached to the side piece of the compartment.

H is the composing-stick. It is so attached to the bar I, which turns on a pivot at i , that it can be swung back and forth in a horizontal plane under the type-case B. It is made of two strips of metal plate or other suitable material parallel to each other at such a distance apart as to hold one line of type as they are set up for printing. The piece h, which forms the front end, extends below the composing-stick and rests on the front part of the frame A.

K is a lever. Its front end forms the handle by which the composing-stick is operated. It has two arms K' K', one on each side of the composing-stick. It has a vertical motion on the pivot k, Fig. 2.

L is a bent lever, turning on a pivot at i . Its horizontal arm is attached to the lever K at k^2 . The upper end passes up through the composing-stick far enough to reach the rods D D under the compartments of the type-case. There is a shoulder l^2 , Fig. 2, which projects over the bottom T of the composing-stick far enough to keep the type from falling through the stick when the lever L is forced back by the rod M. The rod M is attached to the bent lever L by hinge-joints. N is a spring which tends to raise the lever K.

P P are two fingers formed of two long slender strips of metal. Their hinder ends are fastened firmly to the composing-stick, and their front ends enter the composing-stick, one on each side, in front of the bent lever L, as shown at P', Fig. 2.

S is a follower, which fits closely between the sides of the composing-stick, and yet may be easily moved from one end of it to the other, as the type are introduced behind, and are forced against it by the action of the machinery. It has a projection or cap on the top, which keeps it in an upright position, as shown clearly in Figs. 1 and 2. By means of this follower S and the fingers P P the type are held in their place after they are received into the composing-stick.

T is a movable bottom to the composing-stick, by means of which the type may be discharged when the composing-stick is full.

V V are guides for the composing-stick. They are set in the front part of the frame A and correspond in number and position with the compartments in the type-case B. They are so arranged that when the lever K is forced down between any two of them the upper end of the bent lever L will press against the end of the rod D under the compartment that corresponds with the space in which the lever K is forced, and the composing-stick is in the exact position to receive the type from the case.

Mode of operation: When the type are properly arranged in the case, the composing-stick is swung under the required compartment. The lever K is then pressed down between two of the guides V V. As the lever K descends, the upper arm of the bent lever L is forced against the rod D, which actuates the pawl E, carrying the upper end of E toward the composing-stick. This end, catching in the ratchet-teeth of the arm c of the follower C, carries it and with it the type in the compartment resting against it toward the

opening in the front end of the compartment. The type at the end of the compartment, being thus carried beyond the finger G, falls through the opening in the front end of the compartment into the composing-stick H between the upper arm of the bent lever L and the ends of the fingers P P. When the lever K is raised, the upper arm of L drives the type between the two fingers P P, the follower S is pushed back by the pressure on the type, and the type is then held between the fingers P P and the follower S. At the same time the spring F forces the rod D back and the pawl E catches another tooth in the ratchet of the arm c of the follower C. The composing-stick is then swung under the next letter that is wanted, and so on. When the stick is full, the bottom is opened and the line drops through into the column, which is to be on a table directly underneath it. The followers S and C are to be moved back by hand whenever necessary.

Having thus described my invention, what I claim as new, and desire to secure by Letters Patent, is—

1. The follower C, with the arm c, in connection with the pawl E and rod D, or their equivalents, substantially as described, and for the purpose set forth.
2. The finger G or its equivalent, substantially as described, and for the purpose set forth.
3. The composing-stick H, in connection with the lever K, bent lever L, connecting-rod M, spring N, follower S, fingers P P, and bar I, substantially as described.
4. The guides V V or their equivalents, substantially as described, and for the purpose set forth.

HENRY HARGER.
